UNITED STATES PATENT OFFICE.

ANSEL N. HOVEY, OF JACKSON, MICHIGAN.

CHECKREIN-HOOK.

SPECIFICATION forming part of Letters Patent No. 367,400, dated August 2, 1887.

Application filed April 21, 1887. Serial No. 235,642. (No model.)

To all whom it may concern:

Be it known that I, ANSEL N. HOVEY, of Jackson, in the county of Jackson and State of Michigan, have invented a new and useful Improvement in Checkrein-Hooks, of which the following is a specification.

My improvements relate to checkrein-hooks; and the object of my improvements is to provide a hook from which the checkrein is not liable to be accidentally disengaged, and which can be conveniently secured to the harness-saddle. I attain this object by the means illustrated in the accompanying drawings, in which—

15 Figure 1 is a side elevation, and Fig. 2 is a plan, of a portion of a harness-saddle with my improved checkrein-hook attached. Fig. 3 shows my checkrein-hook attached to that kind of harness-saddle in which the check-
20 rein-hook is secured on the upper surface of the saddle instead of between two of the different parts of which the saddle is made.

Similar reference-figures refer to similar parts throughout the several views.

25 1 is a part of the skirts of a harness-saddle. 2 is the seat of a gig saddle. 3 is a checkrein-hook.

The hook 3 is secured to the saddle in the usual ways, and curves forward and upward, then backward and upward, and near its highest part divides into two forks, 4 and 5. The forks 4 and 5 bend away from each other and backward and downward to near their ends, where they come at opposite sides of and below the highest part or ridge of the saddle. From this point they may bend upward to their ends. Said forks should separate far enough to leave space for the checkrein to readily pass edgewise between their lowest
35 40 part and the saddle.

The method of adjusting the checkrein to and the operation of my improved checkrein-hook are as follows: The checkrein is bowed over the top of the saddle and passed edge-
45 wise between the saddle and the forks 4 and

5, and rests in the bend of the hook 3. It will be noticed that if the checkrein is thrown backward by the motion of the horse's head or otherwise, it will strike against the forks 4 and 5 and the top or ridge of the saddle, and be prevented from disengaging, while it may be readily disengaged by hand in a manner similar to that described for inserting it into the hook.

In checkrein-hooks heretofore used the prong of the hook comes over the bolt 6, by which bolt the seat is secured to the saddle-tree in that kind of saddle shown in Figs. 1 and 2. This makes it difficult and inconvenient to insert said bolt into the hole prepared for it, and frequently causes the person putting the parts of the saddle together to mar the surface of the seat or the head of the bolt. This difficulty is obviated in my improved hook, as the forks 4 and 5 separate sufficiently to permit of the bolt 6 being dropped vertically into place between them.

The method of adjusting my improved checkrein-hook to harness-pads for teams is entirely similar to that herein described for adjusting it to the harness-saddles for single horses, and therefore requires no separate description.

Having fully described my invention, what I wish to claim and secure by Letters Patent is—

1. A checkrein-hook having its prong divided into two gradually-diverging forks, substantially as shown and described.
75
2. The combination, with a harness saddle, of a checkrein-hook bent backward over said saddle and divided into two forks, said forks extending near to and below the highest part of the saddle, substantially as and for the purpose described.

In witness whereof I have hereunto affixed my hand and seal this 18th day of April, 1887.

ANSEL N. HOVEY. [L.S.]
